UNITED STATES PATENT OFFICE.

JULIUS H. PRATT, NEW YORK, N. Y.

IMPROVEMENT IN IVORY-COVERED BOOKS.

Specification forming part of Letters Patent No. 42,507, dated April 26, 1864.

To all whom it may concern:

Be it known that I, JULIUS H. PRATT, of the city and county of New York, State of New York, have invented a new and useful Improvement in Ivory-Covered Books; and I do hereby declare that the following is a full, clear, and exact description thereof, reference being had to the accompanying drawings, making a part of this specification, in which—

Figure 1 is a perspective view of a photograph-album having my invention applied to it. Fig. 2 is a sectional view representing the construction of the covering. Fig. 3 represents the mode of producing the sheets of ivory from the tusk.

Similar letters of reference indicate corresponding parts in the three figures.

My invention consists in the employment of ivory, when prepared in a particular manner, for the covering of albums and other books wherein ornamentation and a neat exterior finish is desirable, as will be hereinafter described.

To enable others skilled in the art to make and use my invention, I will describe its construction and operation.

Animal ivory is susceptible of receiving a very fine gloss and of retaining this gloss for an indefinite length of time. This peculiarity, together with its beauty and durability, renders it a very desirable material for the outside leaves or covering of books; but the objection to using ivory for this purpose has hitherto arisen from the fact that the transversely or laterally cut slabs are necessarily so very small and the production of slabs in this way attended with so much waste of stock that other and less expensive materials have been used in its stead. Other and greater objections to the use of cross-cut ivory for this purpose are, the difficulty of uniting the slabs permanently together for large book-covers and the liability of the slabs cracking in the ordinary use of the books.

The preparation of the ivory for my improved method of adapting it for use as book-covers consists in first reducing the tusk to a cylindrical form and subjecting the cylinder to a saw adapted to the purpose, by means of which the cylinder is cut from the circumference to the center in the form of a scroll or convolute sheet. By this mode of cutting sheets of ivory from tusks I am enabled to pro-

duce all the flexibility required for my purpose, and the surfaces of the sheets will receive a much finer polish than slabs of ivory cut diametrically and longitudinally through the tusk. The clouded and waved appearance of the cross cut ivory is almost obliterated by the mode of cutting which I have adopted, and hence it will receive a fine and beautiful appearance by bleaching and polishing, which renders it especially useful for the covering of such books as require a neat and handsome external finish to augment their value. When the large sheets of ivory thus produced have been bleached, pressed, and polished, they are marked and cut according to the different sizes of the books. The slabs should be about the size of the mill-board covers to which they are cemented, as represented in Fig. 2, *a a* being the outside ivory covers and *b b* the inside mill-board to which the ivory is applied. The binding of the book—*i. e.*, the stitching and uniting of the book to the mill-boards *b b*—may be done in the usual or in any desirable manner, after which the outside ivory covering is to be attached either by cementing, riveting, or in any other suitable manner. The book is now finished by binding the edges of the covers so as to protect them from injury. This binding is made of thin, narrow strips of metal, as shown at *e e*, Figs. 1 and 2, bent so as to lap over the edges of the covers and to clamp and hold these edges firmly together. The strips of metal *e'*, which extend across and overlap the back edge of the ivory covering *a a*, serve to tie the ends of strips *e e* together and also to give a finish to the covers. It is obvious that the expense and labor of covering books with scroll-cut ivory will be much less than that attending the use of cross-cut ivory, for in the former instance each side or cover is made of a single or unbroken sheet of ivory of a homogeneous character, while in the latter case the strips or slabs require to be pieced or jointed together for books of common sizes, and these joints are very unsightly and liable to be opened in the ordinary use of the books.

The metallic binding *e e e'* serves not only as an ornament to the covers, but it also prevents the covers from warping and the ivory from splitting in consequence of the exposure of the books to the heat of rooms. The metallic clasps *d d*, represented in Fig. 1, will

also serve to prevent the ivory from warping; and the stiffening-boards *b b*, to which the thin plates of ivory are applied, will give protection and strength to them.

I do not desire to extend my invention to the use of two or more pieces of ivory applied to each side of a book as a covering therefor. Neither do I claim, broadly, covering each side of a book with single unbroken sheets of ivory, for this may have been done before with very small books to a limited extent.

By my invention I am enabled to improve the external appearance and increase the durability of book-covers, and finally to render an ivory-covered book available to the trade as an article of merchandise.

In the cutting of the ivory from the sheets the slabs may be made smaller than the mill-board covers to which they are to be applied, thus leaving a margin around, or partially around, the ivory slab to be covered with velvet, cloth, leather, or some other suitable material.

Having thus described my invention, what I claim as new, and desire to secure by Letters Patent, is—

1. Applying seamless or unbroken sheets of scroll-cut ivory to the mill-board covers of books in combination with the clamping-binding *e e*, substantially as and for the purposes described.

2. As a new and improved mode of preparing covers and covering books with ivory, the scroll-cutting and binding processes combined, substantially as and for the purposes described.

3. The method, substantially as set forth, of manufacturing seamless covers for books from scroll-cut ivory.

4. As a new article of manufacture, a seamless scroll-cut ivory-covered book, substantially as described.

JULIUS H. PRATT.
